Attorneys.

UNITED STATES PATENT OFFICE.

WILLIAM E. TELLING, OF CLEVELAND, OHIO.

DESIGN FOR A MINIATURE BILLBOARD.

57,484.

Specification for Design.

Patented Apr. 5, 1921.

Application filed November 21, 1919. Serial No. 339,704. Term of patent 14 years.

To all whom it may concern:

Be it known that I, WILLIAM E. TELLING, a citizen of the United States, residing at Cleveland, in the county of Cuyahoga and State of Ohio, have invented a new, original, and ornamental Design for Miniature Billboards, of which the following is a specification, reference being had to the accompanying drawing, forming part thereof.

The figure is a plan view of a miniature billboard, showing my new design.

I claim:

The ornamental design for a miniature billboard, as shown.

W. E. TELLING.
